UNITED STATES PATENT OFFICE.

CHARLES H. KNAPP, OF PATERSON, NEW JERSEY.

BAR FOR STRETCHING-MACHINES.

No. 895,868.

Specification of Letters Patent.

Patented Aug. 11, 1908.

Application filed January 8, 1908. Serial No. 409,807.

To all whom it may concern:

Be it known that I, CHARLES H. KNAPP, a citizen of the United States, residing in Paterson, in the county of Passaic and State of New Jersey, have invented a certain new and useful Improvement in Bars for Stretching-Machines, of which the following is a specification.

The invention relates to the bars or "poles" employed in stretching and lustering dyed silk, to support the skeins while the latter are subjected to the strains induced by the drying operation; and the object of the invention is to provide a bar which shall be light, impervious to moisture, unaffected by the acids and chemicals used in the dyeing processes, and which shall present a smooth surface to the silk fibers, and maintain the desired straight cylindrical form.

20 The invention consists in certain novel features of construction by which the above objects are attained, to be hereafter described.

The accompanying drawings form a part of this specification and show the invention as 25 it has been carried out in practice.

Figure 1 is a side elevation, partly in vertical section, showing a portion of a stretching machine equipped with the improved bars. Fig. 2 is a corresponding elevation showing 30 the ends of a pair of bars and the arms with which they are engaged. Fig. 3 is a side elevation of one of the bars on a larger scale, partly in longitudinal central section. Fig. 4 is a transverse section of one of the bars on 35 a still larger scale.

Similar letters of reference indicate the same parts in all the figures.

The bars heretofore employed for this purpose are cylindrical billets of wood, usually 40 about two inches in diameter and of a length corresponding to the arms of the machine, in a machine of the character illustrated they are usually about twentyfour inches. Such bars absorb moisture from the silk and other 45 sources which raises the grain of the wood and tends thus to entangle or catch the fibers of silk and also tends to warp or distort the bars. Metal is objectionable on account of its weight and cost and its liability 50 to stain the silk as the result of corrosion by

the acids in the dyes. These objectionable features are successfully overcome in my improved bar which comprises a cylindrical core A of wood inclosed in a casing B of suitable material to provide the desired qualities and surface. Various materials will serve for the casing, such as celluloid, but my experiments indicate the composition used extensively for insulating purposes in electrical work and known as "indurated fiber" 55 as being best adapted for the purpose.

The fiber casing is produced in the form of a tube having an internal diameter just sufficient to receive the core A fitted snugly therein. This material is comparatively inexpensive, offers a hard smooth surface which improves with use and handling, and is not affected by the dyes. Its resistance to moisture protects the inclosed core, and its weight 65 is but little greater than a corresponding volume of hard wood.

I have shown the bars as serving with a stretching machine having upper and lower arms M¹ radiating from central bosses M which are forced apart by a screw N, but it 75 will be understood that the type of machine is not important. The arms M¹ are slightly grooved to receive the bars and are sufficiently narrower than the latter to insure 80 against contact therewith of the skeins L carried by the bars.

The casing B may be quite thin but should be sufficient to resist the strains of compression to which the bar is subjected and protect the inclosed core from moisture. 85

I claim:—

In a machine of the character described, a bar of wood having a casing of indurated fiber snugly fitted thereto, combined with an arm grooved to receive said bar and narrower than the latter to insure contact therewith of the skeins carried by the bar. 90

In testimony that I claim the invention above set forth I affix my signature, in presence of two witnesses.

CHARLES H. KNAPP.
